UNITED STATES PATENT OFFICE

HENRY L. CROWLEY, OF EAST ORANGE, NEW JERSEY, ASSIGNOR TO HENRY L. CROWLEY & COMPANY, INC., OF WEST ORANGE, NEW JERSEY, A CORPORATION OF NEW JERSEY

INSULATING SPACER

Application filed April 9, 1931. Serial No. 528,730.

This invention relates in general to insulating spacers and more particularly to such spacers as used in radio vacuum tubes for positioning the cathode with respect to 5 the other electrodes.

One of the objects of this invention is the provision of a spacer for supporting the cathode which is so constructed as to give a minimum of leakage between the cathodes 10 and the other electrodes, especially the grid electrode.

A further object of this invention involves the construction of a spacer and its 15 relationship with the cathode to produce a minimum of strains, chemical reactions, including electrolysis at high frequencies and the temperatures involved and leakage.

A further object of this invention is to 20 construct spacers of this nature of magnesia oxide which has a high dielectric resistance at high temperatures.

A further object of this invention is to 25 produce a spacer which is non-porous, smooth or semi-polished or polished.

A still further object of this invention is to produce a spacer for magnesia oxide which is extremely thin but has sufficient 30 mechanical strength for the purposes required.

A still further object of this invention is to so construct the spacer supporting the cathode that there will be a minimum of contact between the two and between the 35 spacer and plate electrode in some of the forms disclosed.

These and many other objects as will appear from the following disclosure are secured by means of this invention.

This invention resides substantially in the 40 combination, construction, arrangement and relative location of parts, all as will be described in detail below.

Referring to the drawing:

Figs. 1 and 2 are top plan views of two 45 forms of spacers;

Figs. 3 and 4 are a top plan view and a side elevational view, respectively, of another form of spacer;

Fig. 5 is still a further modified form; 50 Figs. 6 and 7 are a top plan view and a

side elevational view, respectively, with some parts broken away of a still further modification.

In the manufacture of vacuum devices such as audion tubes used in the radio industry, it is the present practice to support the cathode with respect to the other electrodes by means of insulating spacers made of mica, lava and the like. These spacers are at present so constructed as to effect a maximum area of contact between them and the cathode. By reason of the material used in the construction employed poor insulation results. In the laminated mica structure conduction through the entrained gases occurs. Their insulating properties are further reduced by the deposition on their surfaces of particles of the cathode coating deposits from the magnesia flash, nickel smudge and the like. In addition, these insulators do not have a sufficiently high dielectric distance at the high operating temperatures of such devices.

The general object of this invention is to overcome these difficulties. The magnesia spacer of this invention is composed in part, or is completely made of magnesia oxide in accordance with the disclosure in my copending application Serial No. 332,555, filed January 14, 1929, and my copending application Serial No. 528,732 filed April 9, 1931.

Briefly, such a spacer is made from magnesia oxide and a binder or flux; a mixture of which is fired at the proper temperature to burn out the flux. Where the resulting body is too brittle due to vitrification, I find it desirable as disclosed in my copending cases above mentioned to use precipitated magnesia and talc as the binder or flux. A mixture of these when pre-treated results in a sufficiently strong and yet materially softer body which is easy to grind and machine to desired form. Instead of using precipitated magnesia the metal may be burned to an oxide. Either form of magnesia may be pre-fired before mixing with the talc for the final firing which gives a product which is less liable to shrinkage. It is well to use as pure materials as possible, since impurities tend to cause vitrifica-

tion both in the pre-firing and final firing. The use of talc is important because it results in a relatively soft body.

As far as this invention is specifically concerned, it is immaterial of what substance the spacer is formed or how it is prepared, since the invention in this case is confined to the form of the spacer.

Referring to the drawing, the ceramic cathode supporting body is shown at 1 in the form of a cylindrical rod having two fine longitudinal bores 2. This rod may be made of any desired materials and in accordance with any process, such as that disclosed in my above mentioned applications. Within the fine bores is mounted the cathode or heater (not shown) in the form of a fine wire shaped like a hairpin. At 3 is shown a spacer which is substantially rectangular with its four corners removed. At the center of the spacer is a square hole 4 which is so shaped so as to nicely fit around the support 1 and contact therewith at four points. Surrounding the spacer 3 is the plate electrode 5 which likewise has a very limited area of contact with the spacer 3. The grid (not shown) is supported within the plate and surrounding the cathode and may be partially supported on the spacer or entirely supported from the stem of the tube in any well-known manner. It will be seen by this construction that there is a minimum of area contact between the cathode structure 1 and the plate 5 without in any way detracting from the supporting and spacing functions of the spacer. Another important advantage of this construction is that the openings between the different elements permits of a free circulation of the gases. In other words, ventilating effect is produced which keeps the temperature of the assembly in use at a lower point than it would be if these openings were not provided.

In the modified arrangement in Fig. 2 the spacer 6 is elliptical in outline and is provided with an elliptical opening 7 which holds the support 1 and the plate or grid 5 in proper relation.

In the structure of Figs. 3 and 4 the ceramic supporting rod 8 is square and lies within a circular opening 10 in the circular spacer disc 9.

The modification in Fig. 5 shows a spacer for use with a so-called screen grid tube in which the outer screen grid 10 is in the form of a cylinder closed at one end. The closed end is provided with a relatively large circular opening 11 which is of greater diameter than the diameter of the supporting body 1. Secured to the grid 10, by means of rivets 14 or other suitable fastening means, is the insulating spacer 12 provided with a square central opening 13 through which the insulating body 1 projects slightly.

The modification in Figs. 6 and 7 involves a spacer 15 having radial projections 16. This spacer is provided with an elliptical central opening 17 through which the rod 1 projects. At 5 is the plate contacting with the radial lugs 16. The spacers are also provided with another hole through which the grid supporting wire 18 projects. This wire or rod is provided with a collar 19 against which the spacer rests. The grid can be supported from the rod 18 within the plate 5 and surrounding the cathode support 1.

In all the forms of this device which have been shown for the purpose of illustrating this invention, the area of contact between the spacer and the elements supported thereby is at a minimum and openings are left to give a ventilating effect.

It will be seen from the above disclosure that this invention relates to certain principles of construction which may be embodied in other physical forms than those given for purposes of illustration. I do not, therefore, desire to be strictly limited to the disclosure as given, but rather to the scope of the appended claims.

What I seek to secure by United States Letters Patent is:

1. The combination as described comprising a ceramic support, a ceramic spacer having peripheral lugs, the spacer having an opening through which the support projects of different shape than the cross-sectional shape of the support, and an electrode in contact with said lugs.

2. In an electron discharge device the combination including an electrode and a cathode and an insulator interposed therebetween and in contact therewith for holding them in spaced relation, the cathode passing through the insulator, the cathode having a different cross-sectional shape than the opening in the insulator to provide supporting contact surfaces of limited area and the periphery of the insulator being of different shape than the cross-sectional shape of the electrode to provide supporting surfaces of limited contact.

In testimony whereof I have hereunto set my hand on this 6th day of April A. D., 1931.

HENRY L. CROWLEY.
